EDGAR B. LINNETT, OF NEWARK, NEW JERSEY, ASSIGNOR TO SEARLS MANUFACTURING COMPANY, OF NEWARK, NEW JERSEY, A CORPORATION OF NEW JERSEY.

WARDROBE-TRUNK CLOTHES-CARRIER.

1,272,819.

Specification of Letters Patent. Patented July 16, 1918.

Application filed June 19, 1916. Serial No. 104,396.

To all whom it may concern:

Be it known that I, EDGAR B. LINNETT, a citizen of the United States, residing in the city of Newark, in the county of Essex and 5 State of New Jersey, have invented certain new and useful Improvements in Wardrobe-Trunk Clothes-Carriers, of which the following is a full, clear, and exact description, such as will enable others skilled in the art 10 to which it pertains to make, construct, and use the same, reference being had to the accompanying drawings, and to characters of reference marked thereon, forming a part of this specification.

15 This invention relates to clothes carriers primarily designed to be combined with what are commonly known in the art as wardrobe trunks.

The object of the invention is to provide 20 a simple, strong, inexpensive and thoroughly efficient clothes carrier which is preferably combined with a wardrobe trunk, but which can be combined with any suitable support, such as for instance, a wall or closet, and 25 which consists of a pair of lazy-tongs provided with receiving means to receive the ends of the clothes hangers, said receiving means forming open jaws to readily and conveniently receive the ends of the clothes 30 hangers when the lazy tongs are in extended position, and to form closed jaws to firmly secure and lock the ends of said clothes hangers when the lazy tongs are in closed or contracted position, to prevent accidental 35 displacement of said clothes hangers.

The construction and arrangement of the various parts of my improved device adapt the same to receive a large number of garments or other articles when in extended position and to fold the same into compact form without creasing them when in contracted position.

40 Other objects of this invention, not at this time enumerated, will appear as the description proceeds.

The invention resides in the various arrangements and combinations of parts, as well as in the details of construction of the same, all of which will be hereinafter more 45 fully described and then embodied in the clauses of the claim, it being understood that changes in the precise embodiment of invention herein disclosed, can be made within the scope of the following claims,

without departing from the spirit of the invention or sacrificing any of its advantages. 55

The invention is clearly illustrated in the accompanying drawings, in which—

Figure 1 represents a perspective view of a preferred form of my improved device, 60 showing the same in partly extended position, thus illustrating the crossed-levers of the lazy tongs forming receiving means in the preferred form, in the nature of open jaws, to readily and conveniently receive the 65 ends of the clothes hangers, and from which they can be readily removed.

Fig. 2 represents a front elevation of the same with hangers in place; and

Fig. 3 represents an enlarged fragmentary 70 view of the crossed-levers of the lazy tongs in their closed or contracted position, illustrating the receiving means closed, in order to provide closed jaws to prevent accidental displacement of the clothes hangers. 75

Similar numerals of reference refer to like parts throughout the specification and drawings.

In the said drawings, the reference characters 1—1 represent lazy tongs, the outer 80 ends of these tongs being connected to a handle bar 2, in any desired or convenient manner, but preferably by means of small angle brackets 3—3, by means of which the lazy tongs may be drawn outward into extended position or pushed inward to closed 85 position, and which forms a further means of support, as will be presently described.

Suitably lazy-tongs supporting brackets 4—4 designed to support the lazy tongs 1—1 90 are located in the top of the trunk as clearly indicated in Figs. 1 and 2 of the drawings. The lower ends of said brackets are conveniently secured in any desired manner, to the sides 5—5 of the trunk or the like, and the 95 upper ends 6—6 of which, are preferably secured to a cleat 7 located in close proximity to the top of the trunk.

The upper inner ends of the lazy tongs 1—1 are pivotally attached to the supporting brackets 4—4, near the upper end thereof, in any well-known manner, as by means of rivets or the like, and the lower inner ends of the lazy tongs are slidably mounted on said supporting brackets, also by means 100 of rivets or the like, which have sliding engagement with elongated slots 12—12 105 formed in said brackets, the upper end of

said slots limiting the outward movement of the lazy tongs, and the lower end limiting the inward movement thereof, together with a pair of stops or brackets 8—8, secured in close proximity to the front of the sides of the trunk, said brackets 8—8 consisting of a single piece of suitable metal, the front edges of which are cut out to form convenient receiving and supporting means for the 10 ends of the handle bar 2.

The inner edges of the crossed-levers 13 of the lazy tongs 1—1, above the center and top pivots thereof, are each provided with notched portions 9, which form receiving 15 means when the lazy tongs are in an extended position, as clearly indicated in Fig. 1 of the drawings, said receiving means being in the nature of open jaws, designed to readily and conveniently receive the cylindrical ends 10 of the clothes hangers 11, and to provide closed jaws, as clearly indicated in Fig. 3 of the drawings, to firmly secure and lock the ends 10 of said hangers 11, when the tongs are in their closed or contracted 20 position, to prevent accidental dis-placement of said clothes hangers 11.

It will thus be noticed that I have pro-30 duced a device of the class described, comprising a minimum number of parts, which are made preferably from ordinary sheet metal, the shapes of which are such as to lend themselves readily to manufacture by the use of ordinary punches and dies. Fur-35 thermore, the construction of the device, when in extended position, enables the user thereof to easily remove from the open jaws of the carrier a hanger, and to replace the same, and which when in a contracted position, prevents the removal of said hanger, 40 the crossed-levers of the lazy tongs forming closed jaws.

Experience has demonstrated that the organization above described is a highly ef-45 ficient one, and while the device described is the preferred embodiment of my present invention, I do not care to restrict myself to the exact details of construction, combi-

nation and arrangement herein set forth, it being obvious that minor variations thereof, not involving the exercise of invention, may 50 be made by any skilled mechanic, and such departures from what is herein described and claimed, I consider within the scope and terms of my claims.

Having thus described my invention, what 55 I desire to claim and secure by Letters Patent is:

1. In a clothes carrier, the combination with a suitable support, of a pair of lazy-tong supporting brackets secured thereon, 60 a pair of lazy tongs operatively connected to said supporting brackets, the crossed-levers of the lazy tongs above the center and top pivots thereof each provided with receiving means for receiving and permitting 65 the ready removal of clothes hangers when the lazy tongs are in extended position, said open receiving means forming closures or locking means for locking the said clothes hangers when the device is in 70 contracted position.

2. In a clothes carrier, the combination with a suitable support, of a pair of lazy tongs operatively connected thereon, the crossed-levers of the lazy tongs above the 75 center and top pivots thereof, each pro-vided with open receiving means for receiv-ing, and permitting the ready removal of, clothes hangers.

3. In a clothes carrier, the combination 80 with a suitable support, of a pair of lazy tongs operatively connected thereon, the crossed-levers of the lazy tongs provided with means for receiving and permitting the ready removal of clothes hangers, said 85 means comprising cut-away portions in the crossed-levers to receive the ends of the clothes hangers.

This specification signed and witnessed this 16th day of June, 1916.

EDGAR B. LINNETT.
